224,681

FISHING POLE HOLDER

James J. Dunphy, 610 52nd St.,
Brooklyn, N.Y. 11220

Filed Oct. 13, 1970, Ser. No. 25,466

Term of patent 14 years

Int. Cl. D22—05

U.S. Cl. D22—22

FIG. 7

FIG. 6

FIG. 8

FIG. 9

FIG. 1 is a front perspective view of the fishing pole holder of my new design;

FIG. 2 is a top view thereof;

FIG. 3 is a side view thereof;

FIG. 4 is a partial side view of the back side thereof;

FIG. 5 is a side view thereof;

FIG. 6 is a front perspective view of a second embodiment of the fishing pole holder of my design;

FIG. 7 is a top view of the second embodiment of my design;

FIG. 8 is a side view of the second embodiment of my design; and

FIG. 9 is a partial side view of the second embodiment of my design.

I claim:

The ornamental design for a fishing pole holder, as shown and described.
